UNITED STATES PATENT OFFICE.

HERBERT PEARCE, OF ALTRINCHAM, ENGLAND, ASSIGNOR TO LINOTYPE AND MACHINERY LIMITED, OF LONDON, ENGLAND.

MAGAZINE OF LINOTYPE-MACHINES.

No. 880,568.

Specification of Letters Patent.

Patented March 3, 1908.

Application filed June 24, 1907. Serial No. 380,498.

To all whom it may concern:

Be it known that I, HERBERT PEARCE, a subject of the King of Great Britain and Ireland, and residing at the Linotype Works, Broadheath, Altrincham, in the county of Chester, England, have invented new and useful Improvements in the Magazines of Linotype-Machines, of which the following is a specification.

10 The present invention relates to improvements in the magazines of a linotype machine of the class described in the specification of Letters Patent 436532 September 16th 1890, in respect of matrix stops for the delivery 15 mouths. In this class of linotype machine, the magazine occupies an oblique position on the top of the machine frame. It is not fast to the frame but only lies on it in order that it can be taken off and another magazine 20 equipped with matrices of a different font, substituted for it. Originally this taking off consisted of sliding the magazine up the frame backwards and then lifting it off the machine, the substitution consisting of the 25 like motions in the reverse order. This combined taking off and substitution is known to linotype operators as change of magazine or, shortly, as change. There are ninety 30 columns of matrices in a magazine, those in one column being all of the same character and different from all the others. As the magazine lies in an oblique position, the matrices would all slide out through the delivery mouth, were it not for the escapements 35 which normally retain the respective columns of matrices within the magazine, by being kept engaged with the respective leading matrices. The depression of a key on the key-board, allows a spring attached to each escapement, to disengage the latter from the leading matrix and to, at the same time, engage it with the following matrix, the leading matrix dropping through the delivery mouth on its way to the line assembling 40 mechanism, the said following matrix thus becoming the leading matrix of that column. The ninety escapements are arranged in a row underneath the magazine and close to its delivery mouth, either on the machine 45 frame or on the underside of the magazine. If they are on the magazine, then each magazine to be used on one and the same machine must have its own set of escapements and have them safeguarded from injury during a 50 change and during the time the magazine is off the machine.

It has recently been proposed to effect the change above mentioned by sliding the magazine down the frame frontwards and then lifting it off the machine. But as the top of the machine frame is oblique, a stop had to be provided to prevent the weight of a magazine sliding it down the frame. As this stop was a permanent one relatively to the magazine, it was necessary to provide means for raising the front end of the magazine clear of the stop and to also disengage the row of leading matrices from the escapements if the latter were carried by the machine frame instead of by the magazine. The raising means have either been ordinary lifting handles or an arrangement of cams acting between the bottom of the magazine and the machine frame. This arrangement of cams consists of a rock shaft extending under the front of the magazine and carrying on each end of it, a cam, and a lever to turn it, each lever having a hook upon its outer end. When the magazine is down on the machine frame, the shorter radii of the cams are in contact with the frame and the levers point to the rear of the machine. Pulling these levers forward brings the longer radii of the cams into contact with the machine frame, thereby raising the front of the magazine high enough to clear the stop above mentioned, and makes them project to the front beyond the machine, thereby forming two downwardly inclined rails upon which the magazine can slide, while the two hooks serve as stops to such sliding by being held by the respective levers in the path of two lugs projecting from the rear of the magazine. But before the magazine is moved out of its working position on the machine, all the matrices in it must be locked in it. Several means or matrix stops have been proposed to do this, e. g., a bar (known to linotype operators as a poker) to be thrust transversely through the magazine in front of, or in front of some part of, all the leading matrices, or a longitudinally slotted round bar to be rocked until one side of the slot engages all the leading matrices in practically the same way as the poker.

105 Referring to the accompanying drawings, Figures 1 and 1^a together constitute a side elevation from the right hand of the machine,

the full lines showing the magazine and its supporting frame in the composing position; the dot-and-dash lines showing either the magazine "matrix stopped" and both it and its supporting frame raised ready for the former to be slid down into the A position, or the substitute magazine "matrix stopped" and on the supporting frame, both ready to be lowered into the composing position; 10 while the dot-and-dash lines A show a magazine hanging in front of the machine, either ready for removal or for being tilted and pushed on to the raised supporting frame: Fig. 2, a plan of the lower portion of the magazine and the present invention; Fig. 3, a section on the line 3—3 of Fig. 2; Fig. 4, a side elevation from the right of Fig. 2, and Fig. 5, a section on the line 4—4 of Fig. 4, looking at it in the direction of the arrow.

15 1 is the stationary frame of the machine; 2, the magazine; 3, one of the set of escapements pivoted upon either the frame 1 or upon some piece fixed thereto and independent of both the magazine supporting frame 25 4 and the magazine 2; 5, the transverse rod in the frame 1 on which the frame 4 turns when it is raised or lowered; 6, the transverse bar fast on the bottom face of the magazine 2 near its delivery mouth and 7, one of 30 the notches in the frame 4 in which the said bar engages to hold the magazine on the said frame; 8, the cam on each side of the magazine 2 and fast on a shaft 9 turning in bearings in the frame 4; 10, a roller on the respective side of the frame 1 for the respective cam 8 to rest and turn on; 11, the hand lever fast to each cam 8 for turning both of them simultaneously; 12, the hook at the outer end of each lever 11; 13, one end of a 35 transverse bar fast on the bottom face of the magazine 2 near its entrance mouth, the two ends of the bar projecting laterally beyond the respective sides of the magazine to engage with the hook 12; 14, the top portion 40 of the channeled guide plate down which the matrices pass from the magazine to the assembling mechanism; 15, the distributor; 16, the channeled magazine entrance through which the matrices reenter the magazine 2 after they have dropped from the distributor; 17, the axis pivoting it to the frame 4, and 18, a spring (one on each side of the machine) holding it in working position.

45 19, as shown best in dot-and-dash lines in Fig. 1, is a hollow in each of the levers 11, adapted to fit upon the respective roller 10 as shown in full lines in that figure.

50 So long as the frame 4 and the magazine 2 on it, are in the composing position, the levers 11 are pointing to the rear, the hollows 60 19 in them resting on the rollers 10. When the operator wants to make a "change", he pulls both levers 11 to the front into the dot-and-dash position of Fig. 1. As the 65 cams 8 roll on the rollers 10, their eccentrici-

ties raise the fronts of both the frame 4 and the magazine 2, thereby completely disengaging the latter from the set of escapements 3. The operator then lifts the front of the magazine till the bar 6 is clear of the notches 7 and pulls it to the front till the bar ends 13 come up to the hooks 12, whereupon he lets the magazine swing into a vertical position and then lifts it off the levers 11. The substitute one is then hung on to the 75 levers 11 by its bar ends 13, pushed up the frame 4 till its bar 6 engages in the notches 7, and both levers 11 reversed, thereby lowering both frame 4 and substitute magazine into the composing position. All the parts 80 and operations just enumerated are either present in the linotype machines of commerce or described in the specifications of improvements thereof.

I will now proceed to specify the present 85 invention.

20 (see Fig. 3) is a slot in the top plate of the magazine and extending across it for the full width of all the matrix grooves therein.

21 is a rock shaft slotted longitudinally so 90 as to produce two faces 22, 23, at an obtuse angle with each other, and turning in suitable bearings 24, 24 fixed to the magazine. For the sake of convenience, but only for that, the face 22 is shown as engaging with 95 the top lug 27 of a leading matrix instead of with the foot 28 of the latter.

29 is a half crank fast on each outer end of the shaft 21 and having its outer end connected by a link 30 to a slide 31 mounted to 100 slide in a direction parallel with the fore-and-aft median line of the magazine, in suitable guides on a suitably shaped block 32 fast to the respective side of the magazine.

The invention requires a detent capable of 105 automatically locking the shaft 21 in the "matrix stopped" position and of being disengaged from the shaft just before the latter is to be unlocked. This detent is shown as

110 consisting of two levers 33 each fulcrumed at 34 in the respective bearing 24, and having its front arm kept in contact with the shaft 21 by a spring 35 resilient between its rear arm and the block 32 and having also a shoulder 36 to the rear of the fulcrum 34 and 115 in the rearward path of a stud 37 that projects laterally from the link 30. The relative proportions and positions of the parts 20 to 24 are such, that turning the shaft 21 through about an eighth of a circle in one 120 direction, will move the face 22 into the path taken by one of the lugs of each leading matrix 25, thereby preventing them falling out of the magazine through its delivery 125 mouth (thus "matrix-stopping" the magazine), and up that path far enough to push all the matrices a short distance up the magazine, thereby making the matrices 25 stand clear of the escapement pawls 26, and so far 130 facilitating their reengagement therewith,

while turning it in the other direction will move the said face 22 clear of the said path. There is a slight amount of lost motion or concentricity between each cam 8 and the 5 respective hollow 19, so that the rise of the magazine 2 does not begin until the levers 11 have been moved through a corresponding arc. There is a corresponding amount of lost motion between the pin of the half 10 crank 29 and the link 30, provided by the slot 38, this lost motion showing to the rear of the said crank pin when the magazine is in the composing position.

39 is a tooth fast on the side of each slide 15 31, and 40 is a coöperating notch incorporated with each cam 8 by means of a plate 41 fast thereto in the plane of the respective tooth. When the magazine is in the composing position, the notch 40 embraces the 20 tooth 39—see the dotted lines—not the dot-and-dash lines—of Fig. 1 and the dotted lines of Fig. 4. The first portion of the motion of the levers 11 to the front, pushes the slides 31 in the same direction and takes up 25 the lost motion above mentioned, brings the face 22 up to the lugs 27 of the matrices 25, pushes all the matrices up the magazine 2 for the short distance above referred to, moves, the studs 37 to the front clear of the shoulders 36, and the face 23 to the front of the levers 33 which are thereupon moved down 30 behind it by the springs 35. The following portion of the forward motion of the levers 11 forthwith makes the cams 8 disengage the notches 40 from the teeth 39, this disengagement being the joint result of the forward 35 position of the teeth after a movement parallel with the fore-and-aft median line of the magazine, and the circular movement of the 40 cams about their axes 9. The raising and lowering effect of the cams 8 upon the magazine 2 and frame 4, the sliding of the former down the latter and the levers 11 and the suspension of it from the hooks 12 form no part 45 of the present invention. After the substitute magazine has been duly seated on the said frame and lowered, the reversal of the levers 11 makes the notches 40 reengage with the teeth 39, thereby making the studs 37 50 ride up the shoulders 36 and disengage the levers 33 from the face 23, and turning the rock shaft 21 till the face 22 is out of the path of the matrix lugs 27, whereupon all the matrices in the magazine slide down it until 55 those of the leading row are in proper engagement with the escapement pawls 26. The connection between the cams 8 and the slides 31 may be dispensed with and the latter be worked by hand.

60 To prevent any inaccuracy in the dimensions of either the front of the magazine 2 or of the stationary part that carries the set of escapements 3, preventing the former seating itself properly up in the latter, and also to 65 prevent the said magazine shaking when it is

so seated, each end of the rock shaft 21 carries a second half crank 42 having a stud 43 adapted to engage under a shoulder 44 projecting from the frame 1. This shoulder 44 is not fast to the said frame, but is connected 70 to it by a spring 45 of suitable strength. The stud 43 is engaged with the shoulder 44 by that rock of the shaft 21 which carries the face 22 out of the path of the matrix lugs 27, and vice versa.

75 I claim,

1. The combination with a matrix magazine occupying an oblique position on the machine frame and detachable from the latter, of a longitudinally slotted rock shaft 80 positioned thereon to stop the matrices by being turned into their path, means carried by the magazine for so turning the said shaft, and means carried by the magazine for locking the said shaft in the matrix-stopping 85 position.

2. The combination with a matrix magazine, of a longitudinally slotted rock shaft or matrix stop; slides on the magazine; and links operatively connecting the slides to the 90 said shaft.

3. The combination with a matrix magazine, of a longitudinally slotted rock shaft positioned on the magazine to stop the matrices by being turned into their path; slides 95 on the magazine; and links operatively connecting the slides to the said shaft.

4. The combination of matrix magazine; rock shaft having two faces at an angle with each other and carried by the magazine; 100 slides on the magazine; links operatively connecting the slides to the rock shaft; a slot in the magazine through which the adjacent face on the rock shaft can be turned into the path of the matrices; a detent adapted to automatically engage with the other of the said two faces to lock the shaft with the said adjacent face in the said path and means actuated by the reversal of the slides to disengage the detent.

5. The combination with a matrix magazine having a longitudinally slotted rock shaft positioned thereon to stop the matrices by being turned into their path, slides, and links operatively connecting the slides to the 115 said shaft, of cams turnable about a relatively fixed axis to raise and lower the magazine and having a certain amount of lost motion; and means on the cams to engage and actuate the said slides during the said motion.

6. The combination of stationary machine frame, matrix magazine detachable therefrom; rocking shaft, matrix stop turning in bearings on the magazine; slides on the magazine for reciprocating the said shaft; links 125 operatively connecting the slides to the shaft; and means actuated by the slides to hold the front of the magazine steady on the frame.

7. The combination of stationary machine 130

frame; matrix magazine detachable therefrom; longitudinally slotted rock shaft or matrix stop turning in bearings on the magazine; slides on the magazine for reciprocating the said shaft; links operatively connecting the slides to the shaft; shoulders on the stationary machine frame; and lugs carried by the said shaft adapted to engage with the said shoulders.

10 8. The combination of a stationary machine frame; matrix magazine detachable therefrom; rocking shaft matrix stop turn-

ing in bearings on the magazine; slides on the magazine for reciprocating the said shaft; links operatively connecting the slides to the shaft; means actuated by the slides to hold the front of the magazine steady on the frame; and means for actuating the slides.

In witness whereof I have hereunto set my hand in the presence of two witnesses.

HERBERT PEARCE.
